CLAIM

The ornamental design for a storage container for grocery and trash bags, as shown and described.

DESCRIPTION

FIG. 1 is a front perspective view of a storage container for grocery and trash bags, showing my new design;

FIG. 2 is a rear perspective view of a storage container for grocery and trash bags;

FIG. 3 is a front view of a storage container for grocery and trash bags;

FIG. 4 is a rear view of a storage container for grocery and trash bags;

FIG. 5 is a right side view of a storage container for grocery and trash bags;

FIG. 6 is a left side view of a storage container for grocery and trash bags;

FIG. 7 is a top view of a storage container for grocery and trash bags; and,

FIG. 8 is a bottom view of a storage container for grocery and trash bags.

The broken line portion of the figure drawings show portions of the article that form no part of the claimed design.

1 Claim, 8 Drawing Sheets
